CLAIM

The ornamental design for an electric bicycle, as shown and described.

DESCRIPTION

FIG. 1 is a top-front-left side perspective view of an electric bicycle embodying my new design;

FIG. 2 is a top-rear-right side perspective view thereof;

FIG. 3 is a left side elevation view thereof;

FIG. 4 is a right side elevation view thereof;

FIG. 5 is a front elevation view thereof;

FIG. 6 is a rear elevation view thereof;

FIG. 7 is a top plan view thereof;

FIG. 8 is a bottom plan view thereof;

FIG. 9 is an enlarged and partial perspective view of area 9 in FIG. 1;

FIG. 10 is an enlarged and partial perspective view of area 10 in FIG. 1;

FIG. 11 is an enlarged and partial perspective view of area 11 in FIG. 1;

FIG. 12 is an enlarged and partial perspective view of area 12 in FIG. 2; and,

FIG. 13 is an enlarged and partial perspective view of area 13 in FIG. 2.

The dot-dash broken lines in drawings are provided for annotative purposes to graphically indicate the areas of enlargement. The dot-dash broken lines do not represent actual structure and do not form part of the claimed design.
